(57) **CLAIM**

The ornamental design for a golf target alignment aid, as shown and described.

DESCRIPTION

FIG. 1 is a perspective view of a golf target alignment aid; FIG. 2 is a perspective view thereof in a state of use with disclaimed environmental subject matter; FIG. 3 is a front view thereof; FIG. 4 is a rear view thereof; FIG. 5 is a top view thereof; FIG. 6 is a bottom view thereof; FIG. 7 is a left-side view thereof; FIG. 8 is a right-side view thereof; and, FIG. 9 is a section view thereof taken along the line 9-9 shown in FIG. 3.

The broken lines in FIGS. 1 and 3 depict portions of the golf target alignment aid that form no part of the claimed design. The remaining broken lines in FIG. 2 in form of three sticks depict environmental subject matter and form no part of the claimed design.

1 Claim, 4 Drawing Sheets
